United States Patent Office

Des. 177,643
Patented May 8, 1956

177,643

CARVING AID FORK

Joseph Schoenfeld, Santa Cruz, Calif.

Application October 20, 1955, Serial No. 38,491

Term of patent 14 years

(Cl. D44—29)

FIG -1-

FIG -2-

FIG -3-

Figure 1 is a top view of a carving aid fork, showing my new design;

Figure 2 is a side elevation thereof; and

Figure 3 is a front elevation thereof.

I claim:

The ornamental design for a carving aid fork, as shown.
